(57) **CLAIM**

The ornamental design for a pool table, as shown and described.

DESCRIPTION

FIG. 1 is a perspective view of a pool table according to the present invention.

FIG. 2 is a side elevation view of the pool table of FIG. 1. FIG. 3 is a front elevation view of the pool table of FIG. 1; and,

FIGS. 2 and 3 are drawn in an enlarged scale.

The broken line showing of the pool table pockets is for illustrative purposes only and forms no part of the claimed design.

EX PARTE
REEXAMINATION CERTIFICATE
ISSUED UNDER 35 U.S.C. 307
THE PATENT IS HEREBY
AMENDED AS INDICATED
BELOW.

2

AS A RESULT OF REEXAMINATION, IT HAS BEEN
DETERMINED THAT:

The single claim is cancelled.
